UNITED STATES PATENT OFFICE.

LOUIS WACKER, OF BUFFALO, NEW YORK.

IMPROVEMENT IN LINING BILLIARD-CUSHIONS.

Specification forming part of Letters Patent No. 35,851, dated July 8, 1862.

To all whom it may concern:

Be it known that I, LOUIS WACKER, of the city of Buffalo, county of Erie, and State of New York, have invented a new and Improved Mode of Lining Billiard-Cushions, of which the following is a specification.

The nature of my invention consists in providing a substance which, in combination with other matter, constitutes and forms a "billiard-cushion" both elastic and durable, and not liable to become untrue and otherwise out of order; and I do hereby declare that the following is a full, clear, and exact description of the combination, construction, and operation of the same, reference being had to the accompanying drawings, making a part of this specification, in which—

Figure 1 is a vertical elevation of a section of the outside guard of a billiard-table without its cover or outsidelining, showing the different sections and how formed and combined. Fig. 2 is a vertical elevated end view of the same.

A represents the hand or rest mold; F, the guard-board; E, the cushion chair or seat.

B is a prepared piece of india-rubber.

C is a strip of prepared rawhide.

d is the groove in which the margin of the linings or coverings are fastened.

It is well known that there has not been made an application of any material for surfacing billiard-cushions that has proved entirely satisfactory. My experience in the manufacture of billiard-tables and in repairing them has convinced me that the greatest difficulty existed in the want of a suitable material for coating or surfacing the exposed surface of the cushion. Among the many difficulties which I experienced was the gradual decrease of the reacting force of the ball; second, the angles became more or less untrue by being marred, "broomed," indented, &c. This was more or less occasioned by the instability and want of elasticity of the materials used for surfacing the cushions—such as leather, steel, wood, gutta-percha, &c.—none of which proved capable of sustaining the concussive force of the walls; third, I also have discovered that with any material in common use for covering billiard-cushions a slight change in the temperature or moisture of the atmosphere or in the angle of the surface could not occur without affecting its elasticity.

To make and combine my invention in constructing the billiard-cushion herein described, first, I make the chair or seat of the cushion of any suitable wood (preferring pine) in the form represented by E, Fig. 2; second, I then make in form, as represented by B, a strip or bar of vulcanized rubber, which is secured to E, as represented. I then have a strip of previously-prepared rawhide, (beef's hide preferred,) which has been thoroughly stretched nearly to the extent of its tension and dried, after which it is made of an exact thickness and chemically prepared and subjected to an immense pressure, by which it becomes extremely solid, hard, and elastic, capable of resisting an indefinite amount of concussive force for an indefinite time, and is not affected by any changes of temperature or atmosphere.

The manner of preparing the rawhide is as follows: After the rawhide has been placed in fresh water for several days and perfectly cleaned from hairs, it is split in layers of the required thickness. After this the hide is stretched on a board or on the floor by means of nails, taking the utmost care to prevent wrinkles, roughness, or any inequality. When half dry, the hide is hardened by heavy pressure between hot plates of iron. Thus prepared, this strip of rawhide is then secured to the surface of the rubber, as indicated by C, thus forming an elastic and durable billiard-table cushion.

d is a groove in which the edge of the lining is secured.

D is a piece of india-rubber used when the seat E is required to be joined at angles by miter-joints and placed between the parts of E, thus compensating for contraction and expansion caused by the atmosphere, which also has a material effect upon the cushions, all of which produces much irregularity in the surface as well as the required angle of the cushion.

After repeated experiments and test trials of materials of various kinds for combining and forming a durable, permanent, and at the same time an elastic billiard-table cushion which would insure, first, a reacting force, being given to the ball by the cushion with accuracy and precision at all times in all degrees of temperature and all different states of the atmosphere; second, a device by which the required angle could be truly and correctly

made and retained; third, a material by which a surface could be formed capable of resisting the continued concussive force of the balls without becoming marred and untrue, ("lame;") fourth, producing a surface having an evenness of elasticity which would cause the ball to react with regularity of motion without "jumping," so annoying to the expert.

After having tried a number of articles without obtaining satisfactory results, I tried an experiment with raw beef-hide, and found that it could be so prepared that it would not only become extremely hard, but at the same time produce the required elasticity as well as flexibility, and I found that after a continued use of several months the cushion retained an exact trueness of surface.

Having thus described the nature of my invention, I do not claim any particular form or angle of a billiard-table cushion, nor do I claim any particular form of the seat E nor the material of which it is made; but

What I do claim as my invention, and desire to secure by Letters Patent, is—

The combination of the covering C, of raw-hide prepared in the manner specified, with the billiard-cushion B D E d, constructed and arranged as herein shown and described.

LOUIS WACKER.
